TEA OR COFFEE BAG

Rodney K. Slocum, Pelham Manor, N. Y.

Application October 8, 1936, Serial No. 104,612

2 Claims. (Cl. 99—77.1)

This invention relates to a package comprising a perforate bag containing a material such as tea, coffee, or the like and also to the method and apparatus for producing the same.

5 The invention has for an object to produce an improved package of the character specified, which may be manufactured at a minimum expense and used with advantage and increased efficiency for all of the purposes for which other 10 packages of this character have been used.

Another object of the invention is to provide a novel method of and apparatus for producing the improved package in an efficient and preferably automatic manner.

15 With these objects in view and such others as may appear, the invention consists in the package and in the method and apparatus herein-after described and particularly defined in the claims at the end of this specification.

20 In the drawings the invention is illustrated as embodied in a tea bag and in the apparatus for producing the same, wherein Fig. 1 is a plan view of a blank comprising the inner and outer jackets superimposed on one another for forming the 25 tea bag; Fig. 2 is a diagrammatic view illustrating one step of the method preferably employed in producing a tea bag embodying the present invention; Fig. 3 is a perspective view with parts in section illustrating the completed tea bag; Fig.

30 4 is a view similar to Fig. 2 illustrating a different type of material for forming the tea bag; Fig. 5 is a diagrammatic view illustrating a further step in the method preferably employed in producing a tea bag and Figs. 6 and 7 are views 35 in side elevation and plan respectively of the preferred apparatus for producing the present tea bag.

As far as I am aware prior to the present invention tea bags have been constructed of a single ply of gauze and in order to prevent leakage 40 of the tea through the interstices of the gauze both during shipment and during the use of the tea bag, a very fine mesh gauze has been used. For commercial reasons it is highly desirable to 45 reduce to a minimum the cost of the gauze. In practice it has been found that the cost of gauze forms a substantial part of the cost of a tea bag and accordingly the present invention aims to produce a novel construction of tea bag in which 50 a much coarser and consequently less expensive gauze may be employed in the production of the tea bag and at the same time leakage of the tea out through the interstices of the gauze prevented to the end that tea bags of a construction 55 as will permit efficient extraction of the tea with

minimum contamination of the tea liquor by tea grounds or leaves may be produced more economically than has heretofore been possible.

While in its broader aspects the invention contemplates a novel package for containing various commodities, for purpose of illustration the invention has been herein illustrated as embodied in a tea bag and in a machine for producing a tea bag. In the illustrated machine shown in Figs. 6 and 7, such portions of an automatic tea 10 bag machine of the general construction shown in the U. S. Patent to Doble, No. 1,726,060, dated August 27, 1929, have been herein shown as will enable the different features of the invention to be understood, and except as to details of construction and modes of operation to be pointed out, the present bag forming apparatus may and preferably will comprise the machine illustrated in said Doble patent to which reference may be made for a complete description thereof. 20

In general a tea bag embodying the invention comprises an outer bag 10 and an inner or lining bag 12 and both the outer and inner bag members 10, 12 are of an open structure adapted to permit the extraction of the tea outwardly 25 through the interstices of the outer and inner bag members. The double jacketed bag containing the commodity may be closed in any usual or preferred manner and preferably provided with a handle comprising a string 13 and tag 30 14 as in the conventional form of tea bag.

The inner bag member 12 may comprise a fibrous sheet of a character capable of forming in effect a filter and the outer bag member 10 may comprise a fibrous sheet of a relatively open 35 structure and which in the double jacketed bag forms a reinforcement for the inner or filtering bag member 12. In practice it is preferred to utilize an inexpensive cotton gauze of open structure or coarse mesh as the outer bag member. 40 In practice the inner bag member may comprise an inexpensive paper batt, or loosely formed web, or a perforated paper sheet and in use serves to restrain the tea or the commodity within the bag and to in effect form a filter. 45

Referring now to the drawings, in the illustrated machine the bag forming members 10, 12, preferably in the form of sheets or webs are superimposed over a die 15 and under a forming and filling tube 16 as illustrated in Fig. 2. The 50 outer member 10 is laid on top of the gauze or inner member 12 so that when the forming tube 16 is caused to descend to form the bag as shown in Fig. 5, the member 12 will form the inner jacket and the gauze 10 the outer jacket of the 55

bag. For the convenience of description the inner member 12 will be referred to as the paper and the outer member as the gauze.

When the material comprising the inner member 12 is such as to require perforation, such as some grades of paper, provision is preferably made for performing the operation during the feeding of the web from the supply roll 20, to beneath the bag forming tube 16, and as herein shown, before entering the feed rolls 24, the paper web 12 is guided past a perforating roll 28 which is driven from, and in timed relation to, one of the feed rolls 24, through a chain 30 which runs over a sprocket 32 secured to the feed roll 10 shaft 34, and a sprocket 36 fast on a shaft 38. A gear 40 also fast on the shaft 38 meshes with a gear 42 secured to the perforating roll shaft 44. A supporting roll 46 which cooperates with the perforating roll 28 is also mounted on the 20 shaft 38. The materials thus prepared and cut off are superimposed upon a supporting plate having the opening or die 15 formed therein, and under the forming and filling tube 16. When the character of material comprising the inner member 25 12 is such as to require no perforating, as for example when a loosely formed paper web, such as a batt, is utilized, then the web from the supply roll 20 is fed directly into the feed rolls 24. A perforated sheet is illustrated in Fig. 4.

30 Provision is made for reciprocating the tube 16 vertically to thereby force the paper and gauze down through the die 15 and form them into a pouch bag, and during such movement provision is made for depositing a predetermined quantity 35 of tea or other desired commodity down through the tube 16 and into the interior of the formed bag. With the exception of the provision of the two supply rolls and the perforating rolls, the specific details of the apparatus thus far described and their mode of operation may and 40 preferably will comprise those illustrated in the aforesaid Doble Patent No. 1,726,060, to which reference may be made for a complete description thereof.

45 As the double jacketed pouch bag is formed and filled in the manner described at the bag forming and filling station of the machine, provision is preferably made for inserting it between one set of double gripping jaws 50, 52 which are automatically opened at this station. After the bag has been formed and filled, the double gripping jaws are closed, thus closing the mouth of the bag, gripping the mouth portion at two points spaced a short distance apart, and operatively 55 supporting the bag during the succeeding operations performed thereon, including the trimming of the surplus material from the mouth portion of the bag, the application of a closure for the mouth of the bag and of a handle comprising 60 preferably a string 13 attached to the mouth of the bag and a tag 14 attached to the string as illustrated in Fig. 5.

In the illustrated machine it will be understood that the plurality of sets of gripping members 50, 52 are operatively supported by a rotatable disk or turret 54, and provision is made for intermittently rotating the turret 54 through successive steps by known mechanism as illustrated in said patent above referred to, so that the bag is formed and filled at one station as at A, and the gripping members 50, 52 are then operated to close the mouth of the bag and to operatively support it and convey it during the successive steps through which the turret 54 is rotated until the 70 bag is presented to the mechanism for looping 75

the string around the mouth of the bag, which is located at station B, and then to the mechanism for attaching the tag to the string at a succeeding station, not shown, but located at a point indicated at C. At a succeeding station means are provided for severing the string which up until this point connects two more of the containers together, and finally after the surplus material has been trimmed off the mouth portion of the bag, the jaws are opened and the completed bag is 10 permitted to drop onto a delivery conveyor 56 to be carried away from the machine.

As above set forth, the bag forming and filling mechanism for forming and filling the bag at the station A; the loop applying mechanism for looping the string around the mouth of the bag at the station B; the tagging mechanism for attaching the tag to the string, and the succeeding mechanisms for completing the bag and delivering it onto the outgoing conveyor 56, may and preferably will comprise in details of construction and mode of operation, the corresponding mechanisms illustrated in said Doble Patent to which reference may be made.

From the foregoing description it will be observed that the present double jacketed structure of package enables the use of a relatively inexpensive and relatively open mesh gauze as the outer member of the double jacketed bag. The paper which may be used for the inner bag is relatively inexpensive and the double jacketed tea bag may be produced much more economically than prior bags embodying a single ply of finely woven gauze. In addition the structure of the double jacketed bag enables a more efficient filtering medium to be employed than has heretofore been possible in the manufacture of single ply tea bags. The use of fibrous material in the nature of a paper batt or web serves as an efficient filter when reenforced by the outer gauze bag member, operating to prevent the inclusion of tea grounds or tea leaves in the extract resulting from the use of the tea ball. The illustrated machine and the method of simultaneously feeding the web materials for forming the outer and inner bags enables the double jacketed tea bag to be produced in a most economical and highly efficient manner. If found desirable, the materials for forming the outer and inner bags, such for example as the paper web and gauze web, 45 may be combined into a composite structure capable of being handled as a unitary single web of material upon the paper making machine, or such materials may be combined by any usual or preferred form of combining apparatus before 50 being fed into the tea bag forming machine.

While the preferred embodiment of the invention has been herein illustrated and described, it will be understood that the invention may be embodied in other forms within the scope of the 60 following claims.

Having thus described the invention, what is claimed is:

1. A tea bag comprising a double jacketed bag and a quantity of tea within said bag, the outer bag being of the pouch type and comprising a relatively coarse open mesh fabric for supporting and reinforcing the inner bag, the mesh size of said fabric being sufficiently great that at least a portion of said tea will pass therethrough, the 65 inner bag being of the pouch type and comprising a porous paper material having small interstices capable of acting as an efficient filter, said inner bag preventing the passage of tea through the meshes of said mesh fabric and the outer bag 70 75

forming a supporting and reinforcing covering for the inner bag, and a fastening device for closing the contracted neck portions of the outer and inner bags.

5. 2. A tea or coffee bag comprising a double jacketed bag of the pouch type, a quantity of the commodity within the bag, the outer bag comprising an inexpensive and relatively coarse mesh gauze having a mesh size sufficiently large that

at least a portion of said commodity will pass therethrough, the inner bag comprising an inexpensive porous paper sheet for preventing such passage of said commodity through the meshes of the outer bag, both bags being of the pouch type and having their neck portions contracted and closed and a handle comprising a string secured to the contracted neck portions of the bag.

RODNEY K. SLOCUM.
